**LOADING AND UNLOADING SYSTEM FOR
BLENDERS AND THE LIKE**

John L. Muench, Short Hills, N.J., assignor to General Machine Company of New Jersey, Inc., Newark, N.J., a corporation of New Jersey

Filed Jan. 9, 1961, Ser. No. 81,401
3 Claims. (Cl. 141—172)

The present invention relates to a mechanism for loading and unloading rotatable blenders, in which the containers usually of cylindrical type are moved under the blender by means of a platform, cart or roller conveyor on which the container may be mounted and which may be automatically or manually caused to pass the blender to be emptied or filled and then removed in similar manner after the blending operation has been completed and the container has been filled with material from the blender.

In the preferred form of the invention, the open top container is brought up by suitable elevating mechanisms which may consist of pneumatic or hydraulic lifting or clamping elements or even screw actuators or elevators.

Desirably, the blender which may be of double conical shape mounted on side trunnions has a clean out side at one of its narrow dimensions or diameters and has a valve side at its other narrow or smaller dimension or diameter.

In operation, the valve side will be on top, and the valve will be closed except during filling or discharging of blending.

The clean out side will normally be on the bottom and only on top when the container is being attached or detached from the valve side of the blender.

Desirably, when the container having therein the material to be discharged into the blender is transported under the blender with the valve side down, the platform or other carrier of the container is caused to move up until the open top of the container is clamped tightly against the valve case.

This may be accomplished by having hydraulic or pneumatic cylinders or other actuators connected on each side of the container and also extending to the platform or carrier for the container.

Then the blender is caused to rotate with the container clamped thereto, and at a certain point, say about 120° from bottom position, the valve is automatically or manually opened, and the material is dumped into the blender, and the blender is caused to continue its rotation until for another 120° within which movement the dumping is completed.

Then the valve is automatically or manually closed, and it will stay closed within the balance of the 120° movement.

At this stage, the blender will have passed through 360°, and the container will be in vertical lowermost position and may be manually or automatically released by means of the carrier or platform as the case may be as a result of the release movement of the pneumatic or hydraulic cylinders.

Usually, the valve will be open at the top of the circuit, and desirably for at least 90° or 120° across the top of the circuit, and the valve may be opened or closed gradually above 90° on the way up and before 90° on the way down.

It is also possible to stop the loading movement of the blender so that the container may be held in inverted vertical position or only slowly moved through the dumping position at 180° to its initial attachment position.

After the container has been dumped and then released, the blender is operated without the container attached thereto until the operation is completed.

Then the same or different container may be attached in the same manner, and the dumping sequence is carried on.

In this sequence, the valve is opened with the container attached thereto and with the container in upright position.

The blender may be dumped by permitting it to move through the lower 45° or 90° with the container attached thereto, and the valve opened or a shaker or vibrator may be employed.

Desirably, the sequence of opening and closing the valve during the respective loading and unloading operations may be accomplished by cam arrangements on the main shaft which will actuate valves or micro-switches connected to electrical motors or hydraulic or pneumatic cylinders operating the valve arrangement as well as a hydraulic or pneumatic lowering or elevating mechanism for the drum carrier or platform.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings, wherein like reference characters denote corresponding parts throughout the several views:

FIG. 1 is an end elevational view of the blender showing the container attachment system.

FIG. 2 is a side elevational view taken at 90° from the showing of FIG. 1.

Referring to FIG. 1, the blender shell A has a man-hole cleaning opening or cover B and an automatically or hydraulically actuated arrangement C.

The container has the bearing trunnion D and the drive trunnion E which are mounted upon the side triangular support structures F and G.

The connecting pipe H for admitting or removing suitable fluid or gas into the shell A may be provided with a rotating, tight joint connection J (see FIG. 1) and with a drive motor K mounted on the platform structure L.

The reduction box arrangement M is positioned closely adjacent to the motor associated with the drive trunnion with the automatic stop and positioning element N which forms no part of this invention but which is used as a valve control lever to open and control the movement of the blender.

The switch or lever arrangement P may be utilized to slow or control the movement.

The container Q which may be of a large size Q₁ or a small size Q₂ is provided with the platform or carrier R which may have a series of rollers S and side stand legs T.

The platform or carrier R is provided with the side pneumatic or hydraulic cylinders or motors V to elevate or lower the carrier R together with the containers.

The actuator which may include hydraulic or pneumatic cylinders X is positioned at the side of the valve housing C.

The starter button and electrical controls may be positioned at Y.

The present invention is particularly directed to the system of providing a carrier which will permit the container to be clamped up against the blender.

The carrier as shown in FIG. 2 may consist of the platform R and the legs T which may carry the container Q on a conveyor, on wheels or on the rollers S.

When the container Q is moved under the valve chamber C by manual or automatic means, the cylinders V may be caused to elevate the platform R and clamp it over the top 20 of the container Q₁ against the periph-

eral gasket 21 or other sealing means at the lower part of the valve housing as is shown diagrammatically partly in section in FIG. 2.

The sealing ring 22 may be provided around the container.

The gasket 21 should be of sufficient width so as to match the top of the various diameters of containers to be used.

The container when gripped or clamped against the valve housing C may then be removed from the runway 10 or conveyor indicated by the arrows 23 and 24.

The connections at 25 and 26 of the piston rods W to the carrier platform R will hold the container tightly up against the valve housing C.

The blender then may be caused to rotate as indicated by the circular dot and dash line 27 to a position 180° away as indicated by the dot and dash lines at the top of FIG. 2.

As the blender is then caused to rotate, the contact of the cams 28 and 29 against the swinging member N 20 may actuate the valve motor X to open or close the same at a position above that indicated by the arrow 30 and at a position below that indicated by the arrow 31.

The pneumatic pressure in the cylinders V as well as in the motor X may be controlled by means of the control means 32 at the side of the blender, and the positioner motor or control 33 shown in FIG. 2 can control the positioning of the blender shell A.

The blender then will return the container Q₁ to the lowermost position indicated at the bottom of FIGS. 1 30 and 2.

As this is being accomplished, the valve C has been closed and the platform R may be lowered.

The blender then may be caused to rotate to complete the blender operation, and when the blending is completed, the container Q may again be attached and the blender shell dumped by means of the pneumatic or hydraulic motors V.

As soon as the blender has been dumped, the valve 40 C again is closed, and the container is removed.

As many changes could be made in the above loading and unloading system for blenders and the like, and many widely different embodiments of this invention could be made without departing from the scope of the 45

claims, it is intended that all matter contained in the above description shall be interpreted as illustrative and not in a limiting sense.

Having now particularly described and ascertained the nature of the invention, and in what manner the same is to be performed, what is claimed is:

1. In a rotatable blender of the type having a support structure and a central cylindrical structure with end conical portions, said end portions converging away from the cylindrical central structure and said conical portions having a manhole cleaning cover at one end portion, an inlet and outlet opening at the other end portion, a trunnion structure carrying the central structure, said trunnion structure being carried by said support structure, and a drive motor on said support structure to rotate said blender on said trunnion structure; a combination therewith of a loading system having a platform positioned adjacent and below the inlet and outlet, actuating cylinders positioned alongside and connecting and extending between the sides of the opening and the sides of the platform, said cylinders moving said platform toward and away from said inlet and outlet opening, said platform receiving a material container to be clamped against said opening and to dump material into and receive material from said opening and means on said platform to permit said container to be moved thereon and therefrom.

2. The blender of claim 1, said blender being provided with an automatic stopping and positioning element to control the position of the blender and to stop it in vertical position.

3. The system of claim 1, said platform being provided with side leg members to support the same and said means on said platform to permit said container to be moved consisting of a plurality of rollers between the actuating cylinders permitting the container to be rolled onto and off of the platform.
